UNITED STATES PATENT OFFICE.

GEORGE JANSSEN, OF QUINCY, ILLINOIS.

COMBINED JACK AND BUMPER FOR AUTOMOBILES.

Application filed December 10, 1923. Serial No. 679,530.

To all whom it may concern:

Be it known that I, GEORGE JANSSEN, a citizen of the United States, residing at Quincy, in the county of Adams and State of Illinois, have invented certain new and useful Improvements in Combined Jacks and Bumpers for Automobiles, of which the following is a specification.

This invention relates to guards or bumpers for automobiles which may be used also as jacks for lifting the machine. It has for its object the provision of a combined bumper and jack which will serve not only as a guard but which may be readily and conveniently transformed into a lifting element, so that any one or more of the wheels of the machine may be lifted from the ground without the necessity of extracting the various tools and implements from beneath the seat of the machine or from tool boxes or other receptacles.

Another object of the invention is to provide a wrench for removing the nuts which secure the rims in place on the wheels; the wrench being a part of the attaching means for the bumper.

Other objects will appear hereinafter.

The invention is exemplified in the combination and arrangements of parts shown in the accompanying drawings and described in the following specification, and it is more particularly pointed out in the appended claims.

In the drawings—

Fig. 1 is a front elevation of an automobile having one form of the present invention applied thereto;

Fig. 2 is a perspective view showing the combined wrench and attaching device for the bumper;

Fig. 3 is a top plan view of the front end of the machine shown in Fig. 1 with a portion of the bumper in section.

Fig. 4 is a side elevation of the parts shown in Figs. 1 and 2 with the bumper arranged in position to serve as a lifting jack;

Fig. 5 is a front elevation of a different type of automobile from that shown in Fig. 1, with another form of the present invention applied thereto;

Figs. 6 and 7 are perspective views of details of my invention;

Fig. 8 is a section on line 8—8 of Fig. 5;

Fig. 9 is a top plan view of the machine shown in Fig. 5 with the combined bumper and jack applied thereto, the device being

shown in broken lines in position to operate as a jack; and

Fig. 10 is a side elevation of the parts shown in Figs. 5 and 9, with broken lines illustrating the position of the invention when operating as a jack.

Referring first to the form of invention shown in Figs. 1 to 4, inclusive, the combined jack and bumper is shown as applied to the front end of a Ford automobile. It will be understood, of course, that the device may be applied in like manner to the rear end of the machine and to other machines than Fords.

In the figures referred to the numerals 12 indicate supporting members bolted or otherwise secured to the frame 13 of the automobile. The forward ends of the bars 12 may be offset downwardly, as shown in the drawing, to bring the bumper more nearly in alignment with the front axle. The shape of the supporting bars will vary for different makes of machines and will also depend on the height at which it is found desirable to support the bumper. Projecting forwardly from the front ends of the bars 12 there are provided bolts or pins 14 having their forward ends threaded to receive holding members 15. Supported by the pins 14 is a plate 16 having slots 17 therein for receiving the pins 14. A pair of bumper bars 18 and 19 are hinged to the opposite ends of the plate 16, as shown at 20 and 21, respectively. These bars when folded against the plate 16 constitute the guards forming the bumper and project laterally an amount equal to the width of the car. They are held in place against the plate 16 by the holding members 15. One of these holding members is shown in detail in Fig. 2 and

may be provided with an extended web member 22 arranged to bear against the bumper bars 18 and 19 and has a threaded opening 23 for receiving the pin 14. The holding member may also be provided with an extension 24 at right angles to the main bar 15, the end of the extension 24 being formed to provide a socket wrench 25 for removing the nuts from the wheel when it is desired to change tires or to remove the rim for any purpose.

It will be understood, of course, that various means may be employed for securing the bumper bars in place against their supporting plate, but the form shown in Fig. 2 is one convenient device for this purpose which also provides a convenient

tool, making it unnecessary to have access to the tool box when it is desired to replace a tire.

To use the device as a jack, as shown in broken lines in Fig. 1 and in full lines in Fig. 4, the holding members 15 are removed and the plate 16 with the bars 18 and 19 is swung in a clockwise direction, viewed in Fig. 1, into the position shown in broken lines 10 in that figure. This will cause the lower bar 18 to take an upright position in which it supports the plate 16 from its hinge 20. The bar 19 is free to swing upon its hinge 21 to act as a lever to lift the car axle 26. When the 15 bar 16 is in its upright position the slot 17 therein will register with the bar 12 so that the entire device may be moved rearwardly to bring the end of the bar 19 beneath the axle 26. It will be apparent that the jack 20 may be adjusted along the front portion of the bar 12 into proper relation to the axle 26. The bar 19 is preferably provided with a retaining pawl 27 hinged to the bar 19 at 28 so that the free end of the pawl 27 will engage 25 a series of ratchet teeth 29 formed on the inner face of a recess 30 in the front face of the plate 16. It will be readily apparent that the pawl 27 will fold into the recess 30, as shown in Fig. 3, when the device is used as 30 a bumper and that the pawl will co-operate with the ratchet teeth to hold the machine in its elevated position when the device is used as a jack. The slot 17 is of sufficient length to permit of the up and down movement 35 of the machine when lifted by the lever 19. When it is desired to lift the wheel at the opposite side of the car, the device is swung about the pin 14 on that side and the bumper bar 18, which is hinged at that end 40 of the plate 16, serves as the lifting lever instead of the bumper bar 19.

In the form of the invention shown in Figs. 5 to 10 inclusive, the supporting brackets for the combined bumper and jack are 45 provided with forwardly bent ends having slots 36 therein, as shown in Figs. 5 and 10. These brackets are secured to the side frame members 33 in any suitable manner, depending upon the frame structure, and in the 50 drawing bolts 34 are shown for this purpose, but it will be understood that the connection with the machine may be changed to conform to the various conditions presented by different makes of machines. Each 55 bracket 31 carries a supporting plate 35 which is provided with a slot 36 extending therethrough, the slot being widened at its outer face, as shown at 37, to accommodate the head 38 of a bolt 39 by which the plate 60 35 is held on the bracket 31. A stop 40 having a curved face, that is shown in Fig. 7, is carried by the bolt 39, which passes through an opening 41 in the stop. A spring 42 surrounds the bolt 39 and bears 65 against the rear face of the stop. The bolt

39 is provided with a nut 43 for regulating the tension of the spring 42. A headed member 44 is provided with a stud 45 which projects through the slot 36 and is threaded into an opening in the end of the bracket 31. The bent end of the bar 31 is somewhat thicker than the main portion so that when the retainer 44 is tightly screwed into the bracket 31 the spring 42 will be placed under tension so as to hold the parts tightly in 75 position without danger of rattling. A pair of bumper bars 48 and 49 are pivoted at 50 and 51, respectively, to the supporting plates 35 at opposite sides of the machine. These bars cross one another in the center, as shown in Fig. 5, and extend laterally a sufficient distance to provide protection for the automobile. Their free ends are held in place against the plates 35 by the holding members 45 and the lower edges of the plates are provided with slightly projecting ratchet teeth 52 which constitute ledges for supporting the free ends of the bumper bars. The studs 45 of the holding members 44 may be provided with socket wrenches for releasing the 80 nuts on the wheel rims in a manner similar to that shown in Fig. 2. Both the front and the rear of the car may be provided with a pair of bumper bars similar to those shown 85 on the front of the machine in the drawing. 90

When it is desired to use the device as a jack the holding members 44 are removed. This will free the plate 35 at the side of the car to be lifted so that it may be swung about the bolt 39 into a vertical position and then carried around the bend in the bracket 31 so that the bolt 39 will have a position transverse to the position of the main bracket 31 and the plate 35 will assume a position 100 against the outer face of the forwardly and rearwardly extending portion of the bracket, as shown in broken lines in Fig. 10. The bumper bar 48 may then be projected beneath the axle of the car by sliding the plate 35 along the bracket 31 into the proper position. This will bring the opposite end of the bar 48 into position to register with the ratchet teeth 52 of the plate 35 so as to hold the power end of the lever down and retain the car in its elevated position. Since a 105 lifting bar is provided for each wheel, any number of wheels may be raised at one time, and in fact the entire car may be lifted from the ground, if desired. This is found advantageous where the car is left unused for a considerable period of time, since it relieves the tires from the weight of the car and thus preserves their strength. 110

It will be seen that a combined bumper and jack is thus provided which is always 115 in position to be used, which does not become misplaced or lost, and which can be applied to the car when desired without the necessity of disturbing the occupants to gain access to tool boxes or storage receptacles 120 125 130

- usually placed under the seats or in other positions which inconvenience the occupants of the car. The device also provides a wrench for removing the rims which is carried in such a position that it is always accessible, so that the entire operation of removing and replacing a tire can be performed without the necessity of tools other than those carried by the bumper parts.
- Having thus described my invention, what I claim as new and desire to secure by Letters Patent of the United States is:
1. A guard for an automobile and means for supporting said guard in position to serve as a lifting lever for raising a portion of said automobile.
  2. The combination with an automobile of means for supporting a bumper bar thereon, said supporting means being shiftable to permit said bar to be used as a lifting lever for said automobile.
  3. A vehicle bumper comprising a pair of guard bars and supporting means for said bars, said supporting means being shiftable to permit one of said bars to act as a lifting lever for one side of said vehicle, and the other of said bars to act as a lifting lever for the opposite side of said vehicle.
  4. The combination with a vehicle of a bar, means for supporting said bar transversely of said vehicle in position to act as a guard therefor, and means for supporting said bar longitudinally of said vehicle in position to act as a lifting lever therefor.
  5. The combination with a vehicle of a bar and a support therefor, said support being movable to permit said bar to be changed from the position in which it extends transversely of said vehicle and serves as a bumper bar into a position in which it extends longitudinally of said vehicle, said support being shiftable when said bar is in said last mentioned position to adjust the end of said bar backwardly in the direction transverse to the axle of said vehicle.
  6. The combination with a vehicle, of a pair of brackets projecting away from one end of said vehicle, a pair of bars supported on said brackets, a plate for holding one of said bars in position on one of said brackets, said plate being movable on said bracket to permit said bar to act as a lifting lever for said automobile, and means for pivotally attaching said bar to said plate.
  7. The combination with a vehicle, of supporting means carried thereby, a pair of bars mounted on said supporting means, and attaching members for securing said bars to said supporting means, said attaching members being movable to bring one of said bars into position to act as a lifting lever one one side of said vehicle, and to bring the other of said bars into position to act as a lifting lever at the opposite side of said vehicle.
  8. The combination with a vehicle, of supporting means secured thereto, a pair of bars mounted on said supporting means, attaching devices for retaining said bars on said supporting means in a transverse position relative to said vehicle to permit said bars to act as guards, said attaching members being shiftable on said supporting means to bring one of said bars into position to act as a lifting lever at one side of said vehicle, and the other of said bars into position to act as a lifting lever at the opposite side of said vehicle, and means for holding said bars when serving as lifting levers in position to sustain the parts raised thereby in elevated position.
  9. The combination with an automobile, of supporting means secured thereto, and a pair of bars pivotally connected to said supporting means at opposite sides of said automobile respectively, said supporting means having parts thereof movable to permit one of said bars to act as a lifting lever at one side of said automobile, and the other of said bars to act as a lifting lever at the opposite side of said automobile.
  10. The combination with an automobile, of a bracket projecting longitudinally of said automobile from one end thereof, a supporting plate mounted on said bracket, means for retaining said supporting plate in fixed position on said bracket when said plate is in one position relative to said bracket, said plate being movable longitudinally of said automobile when in a different position relative to said bracket, and a bar pivotally mounted on said plate and extending transversely of said automobile when said plate is in fixed position on said bracket, but movable into position to engage the axle of said automobile when said plate is shifted to position to move longitudinally of said automobile, and a retaining device for holding said bar in position to sustain a portion of the weight of said automobile when said bar is in said last mentioned position.
  11. The combination with an automobile, of a combined bumper bar and lifting lever therefor, and a holding device for said combined bumper bar and lifting lever, said holding device being provided with a wrench socket.
  12. The combination with an automobile, of supporting brackets secured thereto, a combined lever and bumper bar mounted on said bracket, and a holding device for releasably securing said combined bumper bar and lever to said bracket, said holding device being fixed to said bracket when said combined bumper and lever is in position to act as a bumper, but being removable from

said bracket so as to be free to act as a wrench when said combined bumper bar and lever is in position to act as a lifting lever.

13. The combination with an automobile, 5 of a bracket secured thereto having a bent end, a bar supported on said bracket, and means for securing said bar to said bracket, said securing means being arranged to shift relative to the bent end of said bracket to 10 permit said bar to assume different positions on said bracket.

14. The combination with an automobile, 15 of a pair of brackets secured thereto, separate plates movably mounted on said brackets, a pair of bars pivotally mounted, one on each of said plates respectively, and means for retaining said bars substantially in parallel relation with one another transversely of said automobile, said bars being 20 shiftable into position to act as lifting levers at opposite sides of said automobile respectively.

15. The combination with an automobile,

of a pair of brackets secured to opposite sides thereof, said brackets having longitudinally extending slots therein and having the ends thereof bent to a position substantially at right angles to said brackets, a pair of separate plates mounted on said brackets, each of said plates having slots therein, a bolt extending through the slot in each of said plates and through the slot in the corresponding bracket, springs on said bolts for holding said plates against said bracket, securing devices for locking said plates in position on said brackets, and a pair of bars, one pivoted to each of said plates, said plates being shiftable on said bracket into position to serve as fulcrum members, in which position the bar pivoted thereto acts as a lifting 40 lever for said automobile.

In testimony whereof I have signed my name to this specification on this 7th day of December, A. D. 1923.

GEORGE JANSSEN.
